UNITED STATES PATENT OFFICE.

HARVEY T. LITCHFIELD, OF HULL, AND DAVID RENSHAW, OF COHASSET, MASSACHUSETTS.

UTILIZING EXHAUST-STEAM.

SPECIFICATION forming part of Letters Patent No. 258,932, dated June 6, 1882.

Application filed August 9, 1881. (No model.)

To all whom it may concern:

- Be it known that we, HARVEY T. LITCHFIELD, of Hull, county of Plymouth, and DAVID RENSHAW, of Cohasset, in the county of Norfolk, and all of the State of Massachusetts, have invented a new and useful Improvement in the Process of Utilizing Exhaust-Steam, of which the following is a specification.
- 10 Our invention relates to an improvement in the process of utilizing exhaust-steam; and the invention consists in taking water from a boiler and forcing the said water by pumps or other suitable means under great pressure through a jet-pipe or a series of jet-pipes arranged within the exhaust-pipe of an engine, by which means the water is forced back into the boiler from which it emanated, taking along with it the exhaust-steam.
- 20 The drawing shows a front elevation of the device.
- A represents a boiler in communication with an engine, B, by a steam-pipe, C.
- D is the main exhaust-pipe, connecting engine B with boiler A.
- E represents a pump, of which there may be two or more, the steam ends of which are connected with boiler A by steam-pipe F.
- G is an exhaust-pipe connected with the pumps, and leading into the main exhaust-pipe D.
- H is a tank connected with the pump E by pipes I and J. The pump or pumps are also connected with the boiler by means of pipes J and K, delivering into pipe M, and from thence passing into exhaust-pipe D through a jet-pipe, L.
- The operation is as follows: Steam being raised in the boiler A to the required working-pressure, the pumps are started, causing a jet of water to be delivered from the jet-pipe L under great pressure. The engine B is then

started, the exhaust from which is carried back through exhaust-pipe D to the boiler A by the action of the jet of water issuing from 45 jet-pipe L.

It will be evident that in this process there may be two or more pumps so arranged as to make the pressure and feed to the jet-pipe steady and continuous.

By closing valve N and feeding pumps E from the tank H, or its equivalent, cold water can be forced into boiler A, and so make good any loss by leakage or other cause.

In the accompanying drawing the exhaust-pipe D is shown as entering the boiler A above the water-line; but in general practice it may be found advisable to enter it below the water-line.

What we claim as our invention is— 60

1. The process herein described of utilizing the exhaust of an engine, consisting of first drawing or pumping water from a working-boiler, then forcing it under greater pressure than the boiler-pressure into the exhaust-pipe 65 of an engine, whereby the water and the exhaust of the engine is forced into the same boiler from which they were taken, substantially as described.

2. The combination, in an apparatus for 70 utilizing the exhaust of engines, the boiler A, cylinder B, pump E, with their supply and exhaust pipes, the tank H, and pipes I, J, M, and D, whereby water may be fed to the boiler for leakage and supply, in the manner set 75 forth and described.

In testimony whereof we have signed our names to this specification in the presence of two subscribing witnesses.

HARVEY T. LITCHFIELD.
DAVID RENSHAW.
